UNITED STATES PATENT OFFICE

1,926,493

MACHINERY FOR PACKING CIGARETTES

Walter Everett Molins and John Walker Chalmers, London, England

Application May 27, 1931, Serial No. 540,459,
and in Great Britain June 2, 1930

5 Claims. (Cl. 93—2)

This invention is for improvements in or relating to machinery for packing cigarettes, and refers more particularly to a machine adapted to pack cigarettes in a carton of the type wherein two pockets each adapted to hold a single row of cigarettes, with the cigarettes disposed at right angles to the mouth thereof, are hinged together by a flap which permits the two pockets to be opened out into line with their open ends directed towards one another and extends across the open ends of the two pockets when one is folded upon the other.

The present invention comprises a cigarette packing machine adapted to envelop cigarettes in a carton of the type referred to, which comprises in combination a blank feeding mechanism operable to feed a succession of blanks to a main conveyor having pusher pieces which move each carton blank into a position adjacent to cigarette feeding mechanism, operable to feed two batches of cigarettes on to the said carton with the axes thereof disposed transverse to the direction of movement of the carton and a second conveyor movable in a direction at right angles to the main conveyor operable to receive each loaded carton and convey the same through folding mechanism.

The invention will be more particularly described with reference to the accompanying drawings, in which:—

- 30 Fig. 1 is a plan view of the whole machine.
- Fig. 2 is a front elevation of Fig. 1 in the direction of the arrow "A".
- Fig. 3 is an elevation of Fig. 1 in the direction of the arrow "B".
- 35 Fig. 4 is a section of a portion of Fig. 1 on the line C—C.
- Fig. 5 is a cross section of Fig. 4 taken in direction of arrow "H".
- Fig. 6 is a cross section of Fig. 1 on line D—D.
- 40 Fig. 7 is a section of half the bed of the machine on the line E—E.
- Fig. 8 is a cross section of the bed of the machine on the line F—F.
- Fig. 9 is a similar view on line G—G.
- 45 Figs. 10 to 14 are views of the packet blank in various stages, and will be described in more detail hereinafter.

Referring to the drawings, the cigarettes are fed from a hopper 1 having two distinct sets of 50 vane openings 2 and 3 separated by a spacing member and are removed from the vane openings by a bar 4 carried on the continuous conveyor 5.

The cigarettes are carried across a support 6 55 mounted above the machine bed 7, each batch

of cigarettes delivered thereto by the bar 4 pushing the preceding batch forwards. The support is so shaped that the cigarettes of the set of vane openings 3 will be delivered to a point beyond the centre line of an intermittent chain conveyor 8 60 which carries the carton blanks through this portion of the machine whilst the cigarettes of the other vane opening 2 will be delivered on the near side of the centre line of the conveyor. The conveyor 8 is driven by an intermittent gear consisting of a continuously rotating crank disc 9 65 having a connecting rod 10 attached thereto.

The connecting rod 10 has a projection 11 on the rear side thereof which engages with slots in a disc 12 to which the sprocket wheel driving 70 the conveyor 8 is fixed. As the crank disc 9 revolves, the projection 11 passes out of the slot towards the centre of the disc and enters the next succeeding slot on its return stroke, the swing of the connecting rod moving the disc 12 75 the required amount.

Two patches of cigarettes are simultaneously fed side by side from the hopper 1 and the apparatus is so arranged that the batch from the set of vanes 2 falls on to the portion 13 (Fig. 13) of a 80 carton blank on the near side of the conveyor, whilst the batch of cigarettes from the vane openings 3 falls on to the portion 14 (Fig. 13) of the preceding carton on the far side of the conveyor.

After the conveyor has moved a further stage 85 two more batches of cigarettes are deposited, one of which falls on the portion 14 of the carton, which has previously received a batch on the portion 13 as mentioned above, whilst the other falls on the portion 13 of the next succeeding blank. 90 Thus at each movement of the conveyor one blank passes on from the filling position with two batches of cigarettes.

The carton blanks are fed from a stack 15 by any desired feeding apparatus and delivered to a 95 pair of rollers 16 arranged to score the blanks on the lines about which the folding is to take place. The scored blank is then moved onwards by rollers 17 and deposited above a die 18, Fig. 5, and a plunger 19 descends and presses the blank into 100 the die so that the narrow folds of the longer sides of the blank are bent up.

Fig. 5 shows the forming arrangement in section, from which it will be seen that a plate 20 in the bottom of the die is arranged to grip the blank 105 as the plunger moves downwards in order to secure the correct folding of the blank along the scored lines, the parts 19 and 20 being operated by cams as shown.

The blank is then fed lengthwise by a series of 110

rotating rollers 21 (Fig. 4) and delivered across the bed 7 of the filling portion of the machine so that it lies at right angles to the path of the intermittent conveyor 8.

- 5 One of the pusher pieces 22 of the conveyor contacts with the blank and moves it intermittently along the bed 7 and past the filling position where it receives the two batches of cigarettes in the manner previously described. When the 10 blanks are provided with fingers 23 as shown in Fig. 10, the fingers are preferably given a concave cross section by passing them between forming rollers 24 (Fig. 4) having a series of convex projections and concave depressions, respectively. 15 When the fingers are treated in this manner each finger appears curved when viewed from the outer end, the direction and extent of curvature being preferably such as to conform substantially to the curvature of the cigarette which the finger engages. 20

Where it is desired to have a foil liner in the finished carton, the foil is preferably applied to the carton blank in the following manner. The foil is fed from a reel 25 mounted above the machine, the reel being of a width equal to the length 25 of the foil strip. The foil is fed downwardly by a pair of rollers 26 adapted to emboss a design on the same and from these rollers it passes to another pair of rollers 27 which pull the foil from the embossing rollers. 30

The web of foil next passes into a cutting mechanism, comprising a rotary knife 28 and a soft co-operating roller 29 against which the knife acts, in which a strip of foil of the required width 35 is severed, and at the instant of cutting the leading edge of the foil is seized by a rotary suction device 30 which carries the foil downwards and deposits it flat upon the carton blank, the suction ceasing at the instant the foil comes to rest on 40 the blank.

After the foil has been applied to the blank, the intermittent conveyor moves on another stage and comes to rest with a pair of blanks in line with the two sets of vane openings of the cigarette feed and two batches of cigarettes are deposited 45 upon two successive blanks in the manner previously described, after which the conveyor moves on a stage at a time.

A gripping device 31, Fig. 6, operated by a cam (not shown) is arranged to hold the foil in position on the blank by pressing the latter against a projection 31^a extending downwardly from the plate portion of the member 6 which overlies the bed 7 until the first batch of cigarettes has 50 been deposited thereon. This may be conveniently effected by periodically raising the gripping device or plunger 31 which extends through the bed 7 of the machine to press the blank and foil against the projection 31^a.

During the movement which follows the cigarette feeding, the cover members 32 and 33 are folded over by folding devices, hereinafter described, and the folded blank shown in Fig. 14 is removed by a reciprocating claw 34 into the path of a conveyor 35, this conveyor being of the usual chain type carrying pusher pieces 35^a, which travels at right angles to the path of the intermittent conveyor 8.

In some instances it is desirable to reinforce the hinge member of the double pocket carton, and this is preferably carried out by feeding a strip of material 36 of approximately the same size as the hinge member to the flat carton blank. Mechanism for performing this operation is shown in Figs. 1 and 2 and comprises a magazine

37 from which the strips 36 are fed by an oscillating needle pad 38 to rollers 39 which deliver the strips in turn to an inclined guide 40. The strips are carried down the guide in succession by the pusher pieces 41 of a conveyor 42, and during this movement receive gum on their undersides from a roller 43 receiving gum from a bath 44. It will be understood that in order to avoid the adhesion of the strips to the inclined guide 40, the roller 43 applies the adhesive to points spaced lengthwise of the strip only and the guide 40 is ribbed or otherwise formed to engage with those portions of the strip only which are not supplied with adhesive, this being common practice in the art to which this invention relates. The strips are guided into position on the stationary blanks by an oscillating guide 45 pivoted at 45^a and including a cam follower 45^b rigid therewith, and operated by the cam mechanism 46 and they are subsequently pressed heavily on to the blank at the next stationary position of the conveyor by a vertically moving presser bar (not shown).

In the machine illustrated the carton blank has a series of fingers 23 at each end which are bent over towards the surface of the flaps 32 and 33 for the purpose of retaining the foil in position and also preventing the cigarettes from moving about when the carton is in use.

In order to bend these spring fingers over they are first bent upwards by a cam operated presser 47 (Fig. 7), after which they are turned down on to the face of the blank by a folder 48 to the position shown in Fig. 11.

The fingers are kept in contact with the blank whilst the strip of foil is applied to the blank. The strip is laid on the blank with its extremities on top of the plates which press the fingers down and after the cigarettes have been placed on the blank as shown in Figs. 12 and 13 respectively, the blank reaches the position at F—F, Fig. 1.

Two similar cam operated presses 49, Fig. 8, raise the panels 32 and 33 from the horizontal to the angle shown, bending them about small triangular folders 49^a to properly shape the end of the pockets, the folders 49^a being preferably secured to the bed 7 of the machine at points spaced laterally of the path of the blank, these folders extending inwardly over the blank and having forwardly directed fingers overlying the blank adjacent the cam operated presses 49 as shown in Figure 1 of the drawings, after which folders 50 fold down these panels on to the surface of the cigarettes, thus producing a partly folded carton as shown in Fig. 14. It will be observed from Figure 8 of the drawings that flat plates 49^b of spring steel, which may be secured to suitable brackets M overlying the bed of the machine, lie in close proximity to the upper surfaces of the cigarettes to prevent the latter from becoming displaced.

Immediately before the position F—F, the spring fingers are opened out from the blank by small plates (not shown) to allow the foil to pass between them and the blank.

During the folding over of the panels as shown in Fig. 9, the spring fingers 23 are guided into contact with the panels 32 and 33 by tapering guides 51, shown in Figs. 1 and 9, respectively, as these fingers tend to spring away from the panels and would injure the cigarettes unless positively guided into place.

The carton is then practically finished except that the flaps 52, Fig. 14, have to be folded down into contact with the corresponding flaps 53.

After the carton shown in Fig. 14 is delivered into the path of the conveyor 35 by the claw 34 it is carried along between guides 54 and the side folds 52 have gum applied thereto by gum rollers 54^a rotating in a gum bath 55, Fig. 3, after which the folds are bent down by folders 56 on to the side folds 53 of the lower members of the carton and the carton is carried into a heater box 57 in which the gum is dried.

10 The heater consists of a vertical box 57 in which the cartons are raised by a reciprocating platform 58. When the cartons reach the top of the heater the gum is quite dry and they are carried by a conveyor into a folding device in 15 which one pocket is folded on to the other.

What we claim as our invention and desire to secure by Letters Patent is:—

1. In a machine for packing cigarettes in cartons, the combination with means for feeding 20 a series of cartons through a predetermined path, of means located adjacent the said path for depositing a liner on each carton, means operable in timed relation to said first named means for depositing a batch of cigarettes on the liner, 25 and means for folding a portion of the carton over the liner deposited thereon to retain the latter in position.

2. In a machine for packing cigarettes in cartons, the combination with means for feeding a 30 series of cartons through a predetermined path, of means located adjacent the said path for depositing a liner on each carton, means operable in timed relation to said first named means for conveying a batch of cigarettes transversely of said first named path and depositing the same on the liner, and means for folding a portion of the carton over the liner deposited thereon to retain the latter in position.

3. In a machine for packing cigarettes in cartons of the double pocket type, the combination with means for feeding a series of cartons through a predetermined path with the pockets of each carton aligned transversely of the path, of means adjacent the said path for depositing a liner on each carton across both pockets, and means operable in timed relation to said first means for depositing a separate batch of cigarettes in each pocket on the liner, and means for folding a portion of the carton over each end of the liner to retain the latter in position and on the folded portions of the carton.

4. In a machine for packing cigarettes in cartons of the double pocket type, the combination with means for feeding a series of cartons through a predetermined path with the pockets of each carton aligned transversely of the path, of means adjacent the said path for depositing a liner on each carton and across both pockets, and means operable in timed relation to said first means for feeding separate batches of cigarettes transversely of said path with the axes of the cigarettes extending in the direction of feeding movement thereof, and depositing the same in 100 the carton pockets and on the liner.

5. In a machine for packing cigarettes in cartons, the combination with means for feeding a series of cartons through a predetermined path, of means located adjacent the said path for depositing a liner on each carton, means operable in timed relation to said first named means for depositing a batch of cigarettes on the liner, and means for momentarily gripping the blank and the liner together to prevent displacement of the latter while the cigarettes are being deposited.
